CLAIM

The ornamental design for an animal skinning holder, substantially as shown and described.

DESCRIPTION

FIG. 1 is a front elevational view of an animal skinning holder showing my new design.

FIG. 2 is right-side elevational view, taken along line 2—2 of FIG. 1, the left-side elevational view being a mirror image thereof.

FIG. 3 is a top plan view, taken along line 3—3 of FIG. 1.

FIG. 4 is a rear elevational view, taken along line 4—4 of FIG. 2.

FIG. 5 is a bottom plan view, taken along line 5—5 of FIG. 4.

FIG-3

FIG-4
